CLAIM

The ornamental design for a cooking apparatus, as shown and described.

DESCRIPTION

FIG. 1 is a front perspective view of a first embodiment of a cooking apparatus in accordance with the subject disclosure.

FIG. 2 is top view of the cooking apparatus of FIG. 1.

FIG. 3 is a bottom view of the cooking apparatus of FIG. 1.

FIG. 4 is a front view of the cooking apparatus of FIG. 1.

FIG. 5 is a rear view of the cooking apparatus of FIG. 1.

FIG. 6 is a top perspective view of the cooking apparatus of FIG. 1.

FIG. 7 is a bottom perspective view of the cooking apparatus of FIG. 1.

FIG. 8 is a right side view of the cooking apparatus of FIG. 1.

FIG. 9 is a left side view of the cooking apparatus of FIG. 1; and,

FIG. 10 is a front perspective view of a second embodiment of the cooking apparatus of FIG. 1 indicating surface shading for metal.
